UNITED STATES PATENT OFFICE

GEORGE B. JACKSON, OF THREE RIVERS, MICHIGAN

AERONAUTICAL PROPELLER

Application filed March 2, 1928. Serial No. 258,451.

This invention relates to improvements to an aeronautical motor of the internal combustion type, and it is concerned more particularly with means by which the products of combustion are educted through the blades of an associated propeller, so as to promote the efficiency of the engine and propeller and also reduce the noise thereof. In the accomplishment of this purpose, the engine exhaust is conducted into a revolving hub which carries the propeller blades through which the exhaust is then passed for discharge at points adjacent the tips and trailing edges thereof. The exhaust gases so discharged from the blades will enter spaces wherein is a partial vacuum resulting from rotation of the propeller blades, thus increasing the efficiency of the propeller and reducing the noise incident to rotation thereof. It is possible to so design the propeller openings in relation to the speed of engine operation and travel of the aeronautical apparatus, that the vacuum effect will travel back into the engine so as to permit a change in the timing of the valves thereof, and render possible the use of a lower grade of fuel, such as kerosene, furnace oil, or distillate.

An exemplification of my invention is set forth in the accompanying drawings 30 wherein—

Figure 1 is a front elevation of an aeronautical propeller and motor with which it is associated;

Fig. 2 is a plan view thereof, the front end 35 of the motor alone being shown;

Fig. 3 is an enlarged detail in vertical section taken on line 3—3 of Fig. 1, and shows the propeller advanced about 90°;

Figs. 4 and 5 are similar views taken, respectively, on line 4—4 and 5—5 of Fig. 3;

Fig. 6 is a detail in section taken on line 6—6 of Fig. 4;

Fig. 7 is a detail in section taken on line 7—7 of Fig. 4;

Fig. 8 is a front elevation of the receiving chamber; and

Figs. 9 and 10 are sectional details taken, respectively, on lines 9—9 and 10—10 of Fig. 3.

In the present invention I aim to take ad-

vantage of certain conditions which are present in the operation of an aeronautical motor. Rotation of the propeller creates an air disturbance resulting in the development of a partial vacuum adjacent the tip and the trailing edge of its blades. The rush of air into this void is in large part responsible for the noise attending operation of an aeronautical propeller. It is possible by the means herein disclosed to utilize the products of combustion from the aeronautical motor to muffle this noise. Such an end is achieved by educting the exhaust gases through the propeller blades for discharge at points adjacent such maximum air disturbance, viz., adjacent the tips and also the trailing edges thereof. By so doing, the space into which the air would normally rush becomes filled, at least in part, by the spent gases so as to reduce the noise attendant upon the operation of the propeller blades, and in addition the minus pressure present at such points of discharge tends to draw the spent gases from the explosion chambers of the engine through the exhaust manifolds thereof. These advantages are followed by numerous others affecting the operation of the motor, several of which will be more fully touched upon hereinafter.

By way of exemplification, the drawings herein illustrate a conventional V-type of aeronautical motor A having each block of cylinders equipped with an exhaust manifold 11 to the forward end of which is connected a pipe 12. These two pipes which lead from opposite engine sides are joined to a hollow member B forming a receiving chamber for the products of combustion. This member is located adjacent the front end of the forward motor bearing C, and may be provided, as shown, with cooling fins 14 projecting outwardly therefrom. This receiving chamber may have a floating mounting with no direct connection to the engine, but only to the exhaust pipes 12 which lead therefrom. For this purpose, I utilize studs 15 which project from the forward end of the front bearing C, these pins being adapted to enter into pockets 16 which are provided upon the rear face of the member B. With any desired number of such studs are asso-

ciated compression springs 17 interposed between the front engine bearing and the rear face of the receiving chamber, the purpose being to exert a forward pressure on this 5 member at points which are preferably equidistant from each other and from the axis of the engine shaft.

As indicated clearly in Fig. 3, the shaft 20 of the engine may be tapered at 21 near 10 its forward end in accordance with usual practice. Mounted upon the shaft end is a hub 22 having a semi-spherical forward wall 23. Extending radially and oppositely from this semi-spherical wall are tubular walls 24 15 defining passages which communicate with an annular chamber 25 in the hub. The rear side of this annular chamber is defined by a radial wall 26 in which are provided a plurality of ports 27 separated by relatively 20 narrow webs, all equidistant from the axis of the shaft 20. The radial surfaces 28 defining these ports are slanted in parallelism, as indicated best in Figs. 4 and 7, the purpose being to deflect the course of gases 25 passing therethrough in the direction of hub rotation, and thereby reduce resistance to the flow thereof. These ports open upon the annular receiving chamber B so as to receive 30 therefrom the spent gases which are educted through the exhaust pipes 12. The hub 22 is splined at 30 to this propeller shaft, so as to rotate therewith; the receiving chamber on the other hand remains motionless, consequently I provide for a tight joint between these relatively moving parts. For 35 this purpose, the forward face of the receiving chamber is formed with annular pockets in which may be received packing rings 31, preferably one inside of the circle of ports 27, and the other to the outside thereof. Due 40 to the pressure exerted by the springs 17, the receiving chamber is maintained in close contact with the hub so as to have a leak-proof connection therewith.

45 At the front end of the propeller shaft which is reduced and threaded in the usual manner, I have mounted a nut 32 together with a lock nut 33 by which the hub is secured removably in place. The opposite ends of its 50 radial tubular portions 24 are flanged outwardly at 35. Resting against each of the flanges so provided is the base flange 36 of a hollow blade forming part of the aeronautical propeller, and by means of bolts 37 each blade 55 may be demountably secured to the hub. As shown best in Fig. 3, the inner end of each blade is provided with a tubular extension adapted to fit and extend within the tubular portions of the hub, thereby adding to the 60 strength and stability of the blade mountings. The blades which may be of conventional form, as represented in Figs. 1 and 2, are hollow so as to provide passages clear through 65 to the tip ends. Openings 38 through the blade are provided adjacent their tips and

trailing edges, thereby establishing communication between the passages on the inside and the atmosphere into which the exhaust gases are discharged.

In the operation of an aeronautical engine having the means for discharging exhaust gases herein disclosed, the minus pressure developed at the tip ends and trailing edges of the propeller blades will exert a pulling force extending back into the explosion chambers. 70 The products of combustion are thereby educted through the passages already described and discharged through the blade openings into the atmosphere. This pulling force is supplemented by a centrifugal force 75 created by rotation of the propeller. In addition the constant motion of the propeller tends to cool the blades so as to reduce further the temperature of the exhaust gases which are already cooled to a considerable extent 80 during their travel to this point. These several factors all contribute to an eduction of the gases with less resistance than formerly. The resulting discharge of the exhaust gases 85 into the partial void adjacent the trailing edges and tips of the blades reduces to a marked degree the explosion noises of the engine.

I claim:

1. In combination, an aeronautical internal combustion engine exhaust having a propeller connected for rotation therewith, the propeller comprising a hollow hub mounted on the engine shaft and hollow blades forming a passage communicating with the hub chamber, a member forming a receiving chamber in communication with the propeller hub, a floating mounting for the receiving chamber, and means for educting products of combustion from the engine into the receiving chamber and thence into the hub and through the propeller blades for discharge into the atmosphere.

2. In combination with an aeronautical internal combustion engine exhaust, a hollow member forming a receiving chamber, a floating mounting for said member co-axial with the engine shaft and adjacent one end bearing of the engine, a propeller mounted on the engine shaft adjacent said member, the propeller having a hub and blades, both hollow, and forming a continuous passage in communication with the receiving chamber, there being openings in the propeller blades communicating with the atmosphere, means for guiding said receiving chamber, means for holding said receiving chamber pressed against the face of said propeller; and means for conducting products of combustion from the engine into the receiving chamber and through the propeller blades for discharge into the atmosphere.

3. In combination, an aeronautical internal combustion engine exhaust having a propeller connected for rotation therewith, the

propeller being provided with a chambered hub and hollow blades extended radially therefrom, a hollow member forming a receiving chamber adjacent the hub and in communication with the interior thereof, a stationary floating mounting including studs carried by the engine frame and slidably engaging openings in the hollow member, means forming a seal between said member and the propeller hub, yieldable means for maintaining the member in close contact with the hub, and means for conducting products of combustion from the engine into the receiving chamber from whence the gases are educted through the propeller blades for discharge into the atmosphere.

4. In combination, an aeronautical internal combustion engine exhaust having a propeller connected for rotation therewith, a propeller comprising a chambered hub mounted on the engine shaft and provided with a lateral wall wherein are ports equidistant from the hub axis, hollow blades carried by the hub and provided with openings through the walls thereof, a hollow member forming a receiving chamber positioned adjacent the lateral wall of the hub, the receiving chamber having an opening in one wall thereof which faces the circle of ports in the radial wall of the hub, means providing a seal between said member and hub, a stationary mounting including studs carried by the engine frame and slidably engaging openings in the hollow member, and spring means for yieldingly maintaining the same closely against the hub, and means for conducting products of combustion from the engine into the receiving chamber for eduction through the propeller into the atmosphere.

40 5. In combination, an aeronautical internal combustion engine exhaust having a propeller connected for rotation therewith, the propeller comprising a hollow hub and hollow blades in mutual communication, there being openings through the walls of the blade, the hub being provided with a lateral wall having ports with opposite edges slanted in the direction of propeller rotation, a hollow member having a stationary mounting adjacent the hub and in contact therewith and open upon one face thereof for establishing communication through the hub ports with the interior of the propeller, said mounting including studs carried by the engine frame and slidably engaging openings in the hollow member, and means for conducting products of combustion from the engine through said member and into the hub for discharge through the propeller blades into the atmosphere.

60 GEORGE B. JACKSON.
